SUPPORT

Joseph G. Alusas, Sharon Hill, Pa.

Application July 31, 1935, Serial No. 33,983

3 Claims. (Cl. 47—40)

My invention relates to supports, more particularly to supports for attachment to window frames, and has for an object to provide an improved support of this kind.

5 A further object of my invention is to provide an improved support for potted plants or the like which may be readily attached to a window frame without use of separate fastening devices.

A still further object of my invention is to provide 10 a support having water-retaining means for moistening the plants.

These and other objects are effected by my invention as will be apparent from the following description and claims taken in accordance with 15 the accompanying drawing, forming a part of this application, in which:

Fig. 1 is a perspective view of one form of support constructed in accordance with my invention;

20 Fig. 2 is a sectional view through a window frame having my improved support shown in Fig. 1 attached thereto;

Fig. 3 is a view similar to Fig. 2 but illustrating another embodiment of my support;

25 Fig. 4 is a plan view of the embodiment shown in Fig. 3;

Fig. 5 is a detail view, in perspective, showing the attaching member for the support shown in Figs. 3 and 4;

30 Fig. 6 is a perspective view of a second modification of the supporting member shown in Fig. 5; and,

Fig. 7 is a perspective view of a further embodiment of my invention.

35 Referring now to Fig. 1 which shows a preferred embodiment of my invention, the numeral 10 indicates, generally, the support which is preferably, although not necessarily, stamped or drawn from a sheet material such as, for example, steel or fibre. The support includes a substantially horizontal shelf portion 11 having a downwardly projecting member 12 at one end thereof. The latter includes one or more pointed spurs 13 which may be driven into the sill of 40 a window frame as shown in Fig. 2, which will be referred to hereinafter. The support 10 includes a raised reinforcing wall 14 which is continuous for defining a pool or reservoir 15, and which strengthens the shelf portion 11 against bending.

45 As shown in Fig. 2, the support 10 may be readily attached to a conventional window frame having a sill 16 and a sash 17. The shelf portion 11 of the support rests on the upper portion of 50 the sill and the vertical member 12 is disposed

intermediate the sash 17 and the outer surface 18 of the sill 16, the points or spurs 13 being embedded in the sill 16. In assembling the support 10 to the sill 16, the sash 17 is raised and the support arranged on the sill 16 at the desired location. The vertical portion 12 is tapped by a suitable tool until the spurs 13 are completely embedded in the outer surface 18 of the sill. The window may then be closed. Usually there is sufficient clearance between a sash and sill to 10 accommodate the vertical member 12 of the support 10 as the latter may be formed of thin material due to the strength added by the reinforcing wall 14. However, on very tight fitting frames, the outer surface 18 of the sill 16 may 15 be chiseled out slightly to permit the sash 17 to close with the member 12 between it and the sill 16.

20 The plant pot, shown at 19, is disposed in the pool or reservoir 15 in overhanging relation with respect to the sill. Downward movement of the shelf 11 is prevented by the spurs 13 which are embedded in the sill. Water may be poured into the reservoir 15 for the plant, which water passes to the earth in the pot through the usual opening formed in the bottom of conventional flower pots.

25 In Figs. 3, 4, and 5, I have shown a support including a shelf 21 having a plurality of continuous walls 22 for defining a series of reservoirs 30 23. Accommodation for a plurality of pots 19 is provided in this embodiment. A modified form of attachment to the window frame is shown including members 24 which engage openings 25 formed in the shelf 21 in latching relation. The 35 member 24 includes a spur 26 which is driven into the sill 16 in the manner heretofore described. A hooked latch 27 is formed in the member 24 at its upper end for supporting the shelf 21. As shown in Figs. 3 and 4, the latches 40 27 pass through the openings 24 and engage the upper surface of the shelf 21. The latter is prevented from becoming disengaged from the latches 27 by the sash 17 which is engaged by an end of the shelf 21.

45 While the member 24 shown in Fig. 5 is of rectangular cross-section, it will be apparent that, if desired, the upper portion thereof may be formed of circular cross-section as shown in Fig. 6 at 27'.

50 Reference will now be had to Fig. 7 which discloses a support similar to the one shown in Figs. 1 and 2 but which is provided with reinforcing walls or ribs 31 extending longitudinally of the shelf portion 11. Preferably, the ribs 31 connect 55

with the wall 14 and extend to adjacent the vertical member 12. By providing the support with these reinforcing ribs 31, I am enabled to form the support from a thinner material than is necessary for the support shown in Figs. 1 and 2.

From the foregoing, it will be apparent that I have provided a novel support for potted plants which may be readily attached to a window frame. The support may be produced economically and 10 may be attached without the employment of a skilled mechanic and without the use of fastening devices other than those supplied as an element of the support. Furthermore, my support is so constructed and arranged that, as illustrated in 15 Figs. 1, 2, and 7, it may be formed from a single sheet of material. Furthermore, my support provides a reservoir for supplying water to the plant or plants.

While I have shown my invention in several 20 forms, it will be obvious to those skilled in the art that it is not so limited, but is susceptible of various other changes and modifications without departing from the spirit thereof, and I therefore desire that only such limitations shall be placed 25 thereupon as are imposed by the prior art or as are set forth in the appended claims.

What I claim is:

1. In a structure for supporting potted plants

and the like for attachment to a window frame having a sill and a sash, said structure being formed entirely of a single piece of relatively light sheet material; the combination of a substantially horizontal support for disposition upon 5 the window sill in overhanging relation, a vertical flange bent downwardly from an end of the horizontal support for disposition intermediate of the sill and the sash, means formed on the vertical flange of the aforesaid piece of sheet 10 metal for piercing the outer surface of the window sill and for supporting the structure entirely at that end, and a completely circular raised portion formed in the horizontal support and defining an imperforate basin for supporting the plant, for 15 retaining moisture and for stiffening the horizontal support.

2. A structure as claimed in claim 1 wherein the circular portion comprises an annular impression formed in the sheet metal. 20

3. A structure as claimed in claim 1 wherein the circular raised portion is spaced from the vertical flange and wherein additional raised portions are provided in the horizontal support extending between the circular portion and the 25 vertical flange.

JOSEPH G. ALUSAS.
